UNITED STATES PATENT OFFICE.

GEORGE ENGEL, OF WICHITA, KANSAS, ASSIGNOR TO E. P. FOX, OF LIBERAL,
KANSAS.

CLAMP.

Application filed May 21, 1927. Serial No. 193,282.

This invention relates to clamping devices for use in connection with awnings, blinds or shades, but more particularly to an awning for use in connection with the doors or windows of an automobile body of the closed car type, but it is to be understood that a clamping device, in accordance with this invention can be used in connection with awnings for doors and windows of buildings, or for any other purposes for which it is found applicable, and the invention has for its object to provide, in a manner as hereinafter set forth, a clamping device for detachably securing the awning frame, as well as the winding roller for the awning, in position with respect to the window frame of the automobile body without injuring or marring the frame and further whereby the device is so constructed and arranged as to provide a pivot for, as well as means for detachably securing the frame in set position, and further whereby the clamping device will permit of the frame being adjusted to and held in a vertical position to enable the awning body to function as a vertically disposed shade.

Further objects of the invention are to provide, in a manner as hereinafter set forth, a clamping device for the purpose set forth, which is simple in its construction and arrangement, strong, durable, compact, thoroughly efficient in its use, conveniently secured to and removed from position with respect to the frame of the awning body or in co-relation with the winding roller of the awning, and comparatively inexpensive to set up.

With the foregoing and other objects in view, the invention consists of the novel construction, combination and arrangement of parts as hereinafter more specifically described and illustrated in the accompanying drawings, wherein is shown embodiments of the invention, but it is to be understood that changes, variations and modifications can be resorted to which fall within the scope of the claims hereunto appended.

In the drawings wherein like reference characters denote corresponding parts throughout the several views:—

Figure 1 is a fragmentary view in vertical section of the body of an automobile of the closed type, a rolling awning arranged in connection with a window opening of the automobile, and further illustrating the adapta-

tion with the window frame of clamping devices, in accordance with this invention, arranged in co-relation with the winding roller and awning frame.

Figure 2 is a fragmentary view in sectional plane, of the window frame, showing the adaptation therewith of a clamping device, in accordance with this invention for the awning frame.

Figure 3 is a fragmentary view, in elevation of the awning frame.

Figures 4 and 5 are perspective views illustrating the body members of the clamping device employed in connection with the awning frame.

Figure 6 is a fragmentary view in plan of a window frame showing the adaptation therewith of a modified form of clamping device.

Figures 7 and 8 are perspective views of the body members of the clamp of the modified form shown in Figure 5.

Figure 9 is a fragmentary view in sectional plan of the window frame showing still another modified form of the clamping device, in accordance with this invention and arranged in co-relation with respect to the window frame.

Figure 10 is a perspective view of the clamping lever employed in the form of clamping device shown in Figure 8.

Figure 11 is a fragmentary view in sectional plan of the window frame showing the adaptation therewith of still another modified form of clamping device in accordance with this invention.

Figures 12 and 13 are perspective views of the body members of the clamping device of the form shown in Figure 10.

Figure 14 is a perspective view of another modified form of body member for the clamp.

Figure 15 is a fragmentary view in plan of a window frame showing the adaptation therewith of still another modified form of clamping device in accordance with this invention and illustrated further in connection with the spring roller for the awning body, the roller and awning body being shown in dotted lines.

Figure 16 is a perspective view of a wear member employed in connection with the modified forms of clamping devices shown in Figures 11 and 15.

Referring to the drawings in detail 1 denotes the body portion of an automobile of

the closed type and which is provided with a window frame 2 including a stile 3 which is arranged rearwardly of a groove or pocket 4 provided in the sides and top of the frame 5. The groove 4 registers with an opening 5 formed in the window sill 6 and said opening 5 provides the mouth of a pocket 7. The groove 4 has mounted therein a packing member 8. The groove 4 in connection with the opening 5 and pocket 7 is provided for the reception of a shiftable transparent panel or glass 9. The foregoing elements are of known construction, and are illustrated by way of example to show the adaptation therewith of a clamping device or fixture in accordance with this invention, for the awning frame and also for the spring roller for the awning body.

The awning includes a flexible rolling or winding body portion 10 and associated therewith is a spring winding roller 11 of any suitable construction. The body portion 10 is fixed at one end to the roller 11 and winds or rolls thereon. The lower end of the body portion 10 is folded upon itself and the fold is indicated at 12 and fixedly secured in position by holdfast means 13. The fold 12 in connection with the body portion 10 forms a hem 14 in which is mounted the head 15 of a yoke-shaped frame which is employed for adjustably positioning the body portion 10 in the manner shown in full and dotted lines in Figure 1. The yoke-shaped frame includes a pair of arms 16, 17, and each of which is formed with a slot 18 extending lengthwise thereof. The arms 16, 17 are flat or rectangular in cross section, and the head 15 is cylindrical and the diameter thereof is materially less than the width of either of the arms. The fold 12 is secured in position after it has been extended around the head 15 of the frame.

With reference to Figures 2, 4 and 5, the form of clamping device illustrated thereby includes a pair of body members referred to generally by the reference characters 20, 21. The body members are referred to generally by the reference characters 20, 21. The body member 20 is of L-shaped contour and one of its arms is of greater length than the other. That arm of greatest length is indicated at 22 and the arm of shortest length at 23. The arm 22 is of greater length than the width of the stile 3. The arm 23 is formed with a feathered or bevelled transverse edge, as indicated at 24. The arm 22 is formed at its longitudinal center with a lengthwise extending slot 25. The body portion 21 consists of a pair of end portions 26, 27 and an intermediate portion 28. The end portions 26 and 27 extend in parallel planes. The end portion 26 is of greater length than the width of the end portion 27. The end portion 27 is formed with a feathered or bevelled edge 28. The end portion 26 is formed with an

opening 29. The intermediate portion 28 extends at right angles with respect to the end portions 26, 27. The body members 20 and 21 are secured together by a holdfast means consisting of a bolt 30, a washer 31 and a wing nut 32. The bolt 30 has its head indicated at 33 and the threaded portion thereof at 34. The arm 23 of the body member 20 is positioned against the forward edge of the stile 3 and extends into the groove 4 between the packing 8 and the rear wall of such groove. The arm 22 is positioned against the stile 3 and extends rearwardly therefrom. The end portion 26 of the body member 21 is positioned against the inner side of the body member 20, that is the arm 22 of the latter, rearwardly with respect to the stile 3. The intermediate portion 28 of the body member 21 abuts against the rear edge of the stile 3 and the end portion 27 of the body member 21 is extended between the stile 3 and the side of the window frame, see Figure 2. The head of the bolt 30 is arranged against the end portion 26 of the body member 21. The shank of the bolt extends through the opening 29 and also through the slot 25. The washer 31 is positioned against the outer face of the arm 22 of the body member 20 and the wing nut 32 abuts against the washer 31 when the clamp is set in position. The bolt 30 not only provides means, in connection with the wing nut 32, for clamping an arm of the awning frame against the arm 22 of the body member 20, but said bolt 30 further acts as a pivot to permit of the yoke-shaped frame to be swung at any desirable inclination with respect to the window frame.

The point of joinder between the arms 22 and 23 of the body member 20 is rounded as at 35 and the point of joinder between the intermediate portion 28 and the end portion 26 is rounded as at 36, and the end portion 27 at its point of joinder with the intermediate portion 28 is rounded as at 37. The clamping device shown in Figures 2, 4 and 5 is detachably secured in position, with respect to the window frame, without the employment of screws entering the window frame of the stile 3. The body members 20 and 21 coact together, in connection with the holdfast means, to retain the clamp in stationary position with respect to the window frame and further said bolt 30 acts as a supporting means for an arm of the yoke-shaped awning body frame. When the yoke-shaped frame is connected with the body of the automobile, two clamping devices are employed.

With reference to Figure 1, the clamping device employed for use in connection with the frame for the awning body is referred to generally by the reference character 38 and the clamping device which is employed for supporting the spring roller 11 as indicated generally by the reference character 39. The device indicated at 38, is of the same construc-

tion as the device 39, but this latter device is formed with a recess 40 for the reception of the pintle of the spring roller.

With reference to Figures 6, 7 and 8 of the drawings, which discloses a modified form of clamping device, the latter includes a pair of body members 40, 41. The body member 41 is constructed in the same manner as the body member 21 shown in Figure 4. The body member 40 is of the same contour as the body member 20, as illustrated in Figure 5, but said body member 40 is not provided with the slots 35, but is formed with a pair of openings 42, 43. In the form shown in Figure 6, the holdfast means, as illustrated in Figure 2 is not employed, but in lieu thereof the body member 41 is secured to the body member 40 by a holdfast device 44 which extends through the opening 42 formed in the body member 40 and an opening 45 formed in the body member 41. In the form shown in Figure 6 the awning frame, referred to generally by the reference character 46, is secured to the body member 40 by holdfast means 47 which extends through the openings 43. The said holdfast means includes a headed bolt, or washer and a wing nut. The washer is interposed between the nut and the arm of the frame 46. In the form shown in Figure 2, the body members are secured together by the holdfast means, which also acts as a pivot for the awning frame; whereas in the form shown in Figures 6, 7 and 8, the body member 41 is not connected to the body member 40 by the holdfast means for the frame 46.

With respect to the form shown in Figures 9 and 10, the clamping device includes but a single body member and which is of L-shaped contour and indicated at 48 and it is constructed in the same manner as the body member 20, shown in Figure 5 with this exception that it is not provided with the slot 25, but in lieu thereof with an opening 49. The body member 48 is secured in position by a cam lever 50 which is pivotally mounted upon a bolt 51 and engages the rear of the window frame as shown. The cam lever 50 acts to fixedly maintain the body member 48 in position. The awning frame, indicated at 52 is positioned against the body member 48 and extending through the arm thereof is the bolt 51. The head of the bolt 51 is indicated at 53, and interposed therebetween and the frame 52 is a washer 54. The bolt 51 carries a securing nut 55 which abuts against one end of the head of the cam lever 50. The bolt 51 also acts as a combined support and pivot for the frame 52.

In the form shown in Figure 11 the clamping device includes a pair of body members 56, 57 and the former is constructed in a manner as shown in Figure 13 formed with a short and a long arm 58, 59 respectively and with the latter provided with a slot 60 formed with an offset portion 61 at one end for the

reception of the pintle of the spring roller. The body member 56 is of L-shaped contour and has its shorter arm 58 formed with a feathered or bevelled end edge 62. The body member 57 is constructed in a manner as shown in Figure 12 and consists of a pair of arms 63, 64 extending at right angles with respect to each other and each formed with an opening and said openings are indicated at 65, 66 with respect to the arms 63, 64. Carried by the arms 59 and 64 is a securing means 66 for the body members as well as for the awning frame 68 and said securing means is constructed in the same manner as that shown in Figure 2 and indicated at 30. Carried by the bolt 69 of the securing means 67 is a wear member or washer 70 formed with a lug 71 which when the clamping device is employed to provide a combined support and pivot for the frame 68 can seat in the slot of the arm of the frame and when the clamping device is employed to support the spring roller, the lug 70 can seat in the slot 60 of the arm 59. The lug 71 prevents the washer or wear member 70 from shifting around the shank of the bolt 69. The shank of the bolt 69 extends through the opening 66 and slot 30 and the head of the bolt abuts against the arm 64 of the body member 56. Extending through the opening 65 in the arm 63, said opening having a wall thereof provided with threads, is a binding screw 72, which abuts against the rear of the window frame, see Figure 1, and acts as a means for securing the body members in position with respect to the frame and as shown in Figure 11. The washer or wear member 70 is formed with an opening for the passage of the shank of the bolt 69 and which is arranged in alignment with respect to the lug 71.

In the form shown in Figure 15 the clamping device includes a body member 74 and a body member 75. The body member 74 is of the same contour as the body member 56 shown in Figure 10 but the slot 76 formed in the long arm of the body member 74 is not provided with an offset portion 71 but it is provided adjacent the rear end of the slot 76 with a transversely extending slot 77 for the reception of the pintle of the spring roller. Otherwise than that as stated the body member 74 is constructed in the same manner as the body member 56. The body member 75 includes a pair of end portions 78, 79 and an intermediate portion 80 which is angularly disposed with respect to the end portions. The end portion 78 is formed with an opening 79 for the passage of the bolt 80' of a holdfast means for securing the body members 74 and 75 together and said bolt 80' also acts as a combined support and pivot for the awning frame. In Figure 15 the clamp device is shown as employed for supporting the spring roller 11 and a pintle 82 thereof is extended into the slot 77. The form of clamping de-

vice shown in Figure 15 is provided with a wear member or washer 70. The clamping device shown in Figure 15 can be employed for supporting the awning frame or the 5 spring roller, and this statement also applies to the form of device shown in Figure 10. In the form of device shown in Figure 15 the body member 75 is extended between the stile 3 and one side of the window frame. 10 The holdfast means between the body members of the clamping device shown in Figure 15 is constructed to simulate to the holdfast means 30 as shown in Figure 2.

The clamping device, provides means for 15 supporting the awning frame, as well as the spring roller which winds the awning body and each form of clamping device is secured in stationary position with respect to the window frame, without the employment of entering screws therefor and under such conditions the body portion of the car is not marred. Each clamping device can be expeditiously secured in position and removed when occasion requires, and therefore it is 20 thought the many advantages of a clamping device, in accordance with this invention for the purpose set forth, can be readily understood, and although the preferred embodiment of the invention is as illustrated and described, yet it is to be understood that changes 25 in the details of construction can be had which will fall within the scope of the invention as claimed.

What I claim is:

35 1. A clamping device for the purpose set forth comprising a pair of body members of unequal length having spaced angularly disposed means at the fronts thereof for extension into the side of a window frame, the 40 means on one body member extending at right angles to the means on the other body member, and a releasable, combined awning frame supporting, clamping and pivot means extending through said members for securing 45 them together and further for removably connecting them in stationary position with respect to the window frame.

50 2. A clamping device for the purpose set forth comprising a body member having angularly disposed means for extension into the side of a window frame, a cam lever associated with said body member for detachably connecting it to the window frame, and a releasable combined awning frame supporting, 55 clamping and pivot means extending through said body member and cam lever for securing them together and for removably connecting them to the window frame in stationary position.

60 3. A clamping device for the purpose set forth comprising a pair of body members of unequal length having spaced angularly disposed means at the front thereof for engaging the side of a window frame, means for 65 detachably connecting them together for

maintaining them in engaged position with respect to the window frame, and a combined awning frame supporting, clamping and pivot means extending through one of said body members for clamping the awning frame thereto.

4. A clamping device for the purpose set forth comprising a pair of body members, one of said members formed with angularly disposed means at its front for abutting the side of a window frame, the other of said body portions adapted to be positioned rearwardly of the window frame and further abutting against the other body member, means carried by that body member positioned rearwardly of the window frame and adapted to engage with the latter for maintaining the said body members detachably connected with the window frame in stationary positions, and a releasable combined awning frame supporting, clamping and pivot means extending through said body members for securing them together and further for clamping the awning frame in position.

5. A clamping device for the purpose set forth comprising a pair of body members of unequal length having spaced angularly disposed means at the front thereof for extension into the side of a window frame, a releasable, combined awning frame supporting, clamping and pivot means extending through said members for securing them together and further for removably connecting them in stationary position with respect to the window frame, said angularly disposed means formed with a bevelled end, and the angularly disposed means of one body portion extending at an angle with respect to the angularly disposed means of the other body member.

6. A clamping device for the purpose set forth comprising a body member having an angularly disposed forward end for insertion in the sides of a window frame and with said end having a bevelled edge, said member of a length to project rearwardly from the window frame, and means carried by the rear end of said body member for maintaining it in position with respect to the window frame and further providing a combined supporting, clamping and pivot means for an awning supporting frame.

7. A clamping device for the purpose set forth comprising a pair of body members of unequal length, the body member of greater length having its outer end formed with a right angularly disposed portion for extension into the side of a window frame, the other body member having its forward end provided with a right angularly disposed portion of L-shaped cross section for extension into the window frame, said body member of greater length formed with a slot, the said body member of smallest length pro-

vided with an opening, and a releasable, combined awning frame supporting, clamping and pivot means extending through said opening and slot for securing said body members together and further for removably connecting them in stationary position with respect to the window frame.

8. A clamping device for the purpose set forth comprising a pair of abutting body members of an equal length, the smallest of said body members positioned against the rear end of the other of said body members, said body members having their forward

ends provided with right angularly disposed portions to oppose a side of the window frame, and a releasable, combined awning frame supporting, clamping and pivot means extending through said body members for securing them together and further for removably connecting them in a stationary position with respect to the side of the window frame.

In testimony whereof, I affix my signature hereto.

GEORGE ENGEL.
